ADAPTER FOR UNCOILERS

Carl T. Lanstrom and James E. Leaver, Concord,
Calif., assignors to United States Steel Corpora-
tion, a corporation of New Jersey

Application December 5, 1951, Serial No. 260,036

4 Claims. (Cl. 242—78)

1

This invention relates to an adapter for metal strip uncoilers.

One example of an uncoiler with which the adapter of the present invention can be used is shown in Todd Patent No. 2,508,977. Such uncoilers include essentially a pair of spaced apart upright housings, a retractable mandrel which normally extends between the housings and can be received in the central opening of a coil for supporting the latter, a drive means for retracting or extending the mandrel, and adjustable side guide plates for positioning the coil on the mandrel. The mandrel is of fixed diameter and satisfactorily supports coils of a reasonable range of internal diameters. However, when the coil fits too loosely on the mandrel, we have observed that the coil edges tend to become damaged and also that the breaker rolls used for tensioning the strip tend to scratch and mar its surface.

An object of the present invention is to provide an adapter which can be installed in pairs on uncoilers of standard construction for supporting coils of different internal diameter than their mandrels are designed to support.

A further object is to provide an adapter which can be supported on an upright housing of an uncoiler and has coil engaging means of any suitable diameter positioned with the side guide plate of the uncoiler.

In accomplishing these and other objects of the invention, we have provided details of structure, a single form of which is shown in the accompanying drawing, in which:

Figure 1 is a vertical sectional view of an uncoiler equipped with adapters which embody features of the present invention; and

Figure 2 is a vertical sectional view of one of the adapters on a larger scale.

Figure 1 shows an uncoiler which is similar to that shown in the aforesaid Todd patent, but simplified by omission of parts not necessary for an understanding of the present invention. The uncoiler comprises a pair of spaced apart housings 10 and 12, a retractable mandrel 13, and a trackway 14 at the left for supporting the mandrel when retracted. The housings have axially aligned openings 15 and 16 respectively through which the mandrel extends when in its coil supporting position. The uncoiler comprises means, not shown, for moving the mandrel between its two positions. Each of the two housings carries side guide plates 17 of similar construction. These plates are supported on a plurality of rods 18 which extend through openings 19 in the housing. The uncoiler also has drive means for

positioning the guide plates. As illustrated these latter drive means include a pair of double acting fluid pressure cylinders 20, one of which is mounted on the outside of each housing, rack gears 21 carried on the piston rod of each cylinder 20, horizontal shafts 22 which carry pinions meshing with each rack gear, and rack gears 23 carried on one of the rods 18 on each side and meshing with suitable pinions on the same shafts 22. It is seen that lowering of either piston rod and rack gear 21 projects the corresponding guide plate 17 toward the center of the uncoiler, while raising these parts does the reverse.

With the mandrel 13 in its retracted position as illustrated, two adapters 24 constructed in accordance with the present invention can be installed in the uncoiler, one on each housing 10 and 12. These adapters are shown supporting a coil S of strip metal for uncoiling in the same position as the mandrel otherwise supports the coil.

Figure 2 shows the details of an adapter 24. The adapter comprises a sleeve 25 which fits closely within the opening 15 or 16 of one of the housings, but is movable axially therein, a shaft 26 rotatably supported within said sleeve on antifriction bearings 27 and 28, and a cone shaped head 29 removably mounted on the forward end of said shaft. An annular plate 30 is fixed to the forward end of sleeve 25, as by bolts 31, for mounting the adapter on a side guide plate 17 of the uncoiler, as with bolts 32. The means for attaching the head 29 to the shaft includes a key 33 and a retainer plate 34 bolted to the end of the shaft. The rear end of shaft 26 carries a brake drum 35 removably fixed thereto by a similar key 36 and retainer plate 37. The rear end of sleeve 25 carries a brake flange 38 which is removably fixed thereto as by bolts 39 and surrounds drum 35. An air tube 40 is mounted on the interior of flange 38 and is operable with drum 35 for retarding rotation of the shaft 26 and head 29.

Before installation of the adapters, the mandrel 13 is retracted to the position shown in Figure 1 and the heads 29, brake drums 35 and brake flanges 38 of both adapters are removed. One adapter is inserted through each of the openings 15 and 16 of the two housings 10 and 12. Bolts 32 are inserted in the appropriate openings for attaching the plates 30 to the side guide plates 17, after which the heads, brake drum and brake flanges are replaced.

The adapters now can be moved axially by use of the drive mechanism which positions the side

guide plates 17. The cone shaped heads 29 are axially aligned and can be used for supporting a coil S for uncoiling in a similar fashion to the mandrel 13. The heads can be of any desired diameter, whereby the adapters enable the uncoiler to be used for coils of various internal diameters other than that which can be efficiently handled with the mandrel. The only structural change in a standard uncoiler to enable the adapters to be installed is the drilling and tapping of holes in the side guide plates for receiving bolts 32.

While we have shown and described only a single embodiment of the invention, it is apparent that modifications may arise. Therefore, we do not wish to be limited to the disclosure set forth but only by the scope of the appended claims.

We claim:

1. The combination with an uncoiler housing, which has a mandrel opening and carries a side guide plate, of an adapter comprising a sleeve received in said mandrel opening, a plate carried by the forward end of said sleeve and attached to said guide plate, a shaft rotatably mounted in said sleeve, a coil supporting head carried on the forward end of said shaft, and cooperable brake means carried on the rearward ends of said shaft and said sleeve.

2. The combination with an uncoiler housing, which has a mandrel opening and carries a side guide plate and drive means for positioning said guide plate, of an adapter comprising a sleeve received in said opening for axial movement, a plate carried by the forward end of said sleeve and removably attached to said guide plate, a shaft rotatably mounted in said sleeve, a cone shaped coil supporting head removably fixed to the forward end of said shaft, a brake drum removably fixed to the rearward end of said shaft, a brake flange removably fixed to the rearward end of said sleeve and surrounding said brake drum, and an air tube on the inside of said brake flange cooperable with said brake drum for retarding rotation of said shaft and said head.

3. The combination with a metal strip uncoiler which includes a pair of spaced apart housings having axially aligned mandrel receiving openings, a pair of side guide plates one of which is movably supported on each of said housings, and drive means for positioning said guide plates, of a pair of adapters received in said openings and attached to said guide plates to be positioned by said drive means and comprising axially aligned coil supporting heads situated between said housings and brake means situated outside said housings.

4. The combination with a metal strip uncoiler which includes a pair of spaced apart housings having axially aligned mandrel receiving openings, a pair of side guide plates one of which is movably supported on each of said housings, and drive means for positioning said guide plates, of a pair of adapters each of which is received in one of said openings and is removably attached to one of said guide plates to be positioned by said drive means and comprising axially aligned cone shaped rotatable coil supporting heads situated between said housings and brake means for retarding rotation of said heads situated outside said housings.

CARL T. LANSTROM.
JAMES E. LEAVER.
